UNITED STATES PATENT OFFICE.

CLARENCE F. MIESSEN, OF CARROLLTON, KENTUCKY.

FOLDING CRATE.

1,127,909.

Specification of Letters Patent.

Patented Feb. 9, 1915.

Application filed October 9, 1911. Serial No. 653,537.

To all whom it may concern:

Be it known that I, CLARENCE F. MIESSEN, a citizen of the United States, residing at Carrollton, in the county of Carroll, State 5 of Kentucky, have invented certain new and useful Improvements in Folding Crates; and I do hereby declare the following to be a full, clear, and exact description of the invention, such as will enable others skilled in 10 the art to which it appertains to make and use the same.

This invention relates to new and useful improvements in crates and more particularly to that class known as folding shipping crates.

An object of this invention is the provision of a crate consisting of a plurality of hinged members which when folded will be reduced in size so as to require very little space for 20 packing and which when extended will be securely held in its extended position against collapsing.

Another object of this invention is to improve and simplify devices of this character 25 rendering them comparatively simple and inexpensive to manufacture, reliable and efficient in use and readily operated.

With the above and other objects in view which will be brought out in the following 30 detailed description this invention resides in the novel features of construction, formations, combinations and arrangements of parts to be hereinafter more particularly described, claimed and illustrated in the accompanying drawings, in which:—

Figure 1 is a perspective view of one form 40 of my improved shipping crate. Fig. 2 is a longitudinal sectional view thereof, showing the same extended. Fig. 3 is a view similar to Fig. 2, but showing the crate folded. Fig. 4 is a transverse sectional view illustrating the crate extended. Fig. 5 is an end view showing the same folded. Fig. 6 is a perspective view of one of the hinges, and 45 Fig. 7 is a perspective view of one of the connecting rods.

Referring more particularly to the drawings, which illustrate the preferred form of my invention, the numeral 15 designates 50 generally my improved shipping crate, which comprises opposite side and end sections 16 and 17 connected at their lower edges by a bottom 18 and at their upper edges by a closure 19.

55 Each of the sections 16, 17 and 19 consists

of spaced parallel slats 20 connected at intervals throughout their length by brace bars 21. The slats 20 are so arranged at one side of the closure 19 that the vertical slats comprised in one of the end sections extend 60 between the longitudinal slats comprised in the top section or closure. These interlocking terminals of the slats are provided with alining apertures as at 22, for the passage therethrough of a connecting rod 23, which connecting rod produces a hinged connection between the top section or closure 19 and one of the end sections 17. The opposite end of the closure 19 has secured to the opposite sides of the slats L-shaped plates 24, the 65 horizontal portions of which are connected by the means of rods 25 which extend through apertures formed in the ends of the slats and plates 24, respectively. In order to prevent any sliding movement of the plates upon said rods, blocks 26 are interposed between the plates and surround the rods 25.

The depending portions 27 of the L-shaped plates 24 are secured at their terminals to the vertical slats 20 of the other of the end closures 17, which construction produces a hinged connection with this said end and top closure causing the same to lie in spaced relation from the top when folded.

The opposite side of the bottom has secured thereto in slots 28 formed therein, L-shaped plates 29 similar to the before mentioned plates 24. The horizontal portions of the plate 29 are secured rigidly within the slots by means of a pair of connecting rods 30, while each vertical extension 31 of the plates 29 is pivoted at its terminal by means of a connecting rod 32 to the vertical slats 20 of the said end of the crate.

The opposite end of the bottom 18 is provided with a plurality of tongues 33 between which are pivoted the lower ends of the slats 20 of the adjacent end closure by means of a connecting rod 34. The opposite 100 sides 16 are hinged at their lower edges as indicated by the numeral 35 to the opposite sides of the bottom 18 and are adapted to be folded thereon when the crate is collapsed.

The medial portions of the slats 20 of the top 19 are connected by a bar 36 provided at its opposite ends with beveled faces 37, which terminate at a point in spaced relation to the outer edges of the end slats 20. Obviously as the sides are raised this beveled 110

face which rests upon the top rail of the sides 16 forces the closure upwardly until the end of the bar 36 engages the rear faces of said top rails of the sides 16, thereby 5 securely locking the crate in its extended position.

The intermediate of the rails 20 of the top 19 are independently hinged with respect to the remaining slats by severing the 10 bar 21 upon opposite sides of the said slats as indicated by the numeral 38, while interposed between the free ends of the slats is a bar 39 which extends slightly beyond the terminals thereof and between slats 40 which 15 form a continuation of these independently hinged slats 20 which prevents any lateral movement of the same which might serve to loosen the hinged connection or bend the connecting rod 23. The ends of these slats 20 and bar 39 rest upon a cross piece 41 secured to the under side of the slats permitting the same to lie flush with the remaining slats.

A block 42 is interposed between these 25 independently hinged slats 20 and has rotatably secured to its upper face by means of a pin 43 a turn button 44, which may be moved transversely of the top 19 of the crate, thereby permitting the upward movement 30 of the previously mentioned independently hinged slats 20.

In order to provide a closure for one-half of the top section 19 when the hinged section is raised, a supplemental closure 45 35 consisting of longitudinal bars 46 connected at intervals throughout their lengths by slats 47, is hinged to the cross bar 36 and adapted when moved upwardly to have the bars 46 interposed between the rails 20 and 40 the slats 47 in contact with the lower faces of the slats 20 which obviously prevents any further upward movement. This hinged section 45 may be retained in its position by means of turn buttons 48 rotatably 45 mounted upon pins 49 for engagement with the upper faces of the adjacent slats 20. Manifestly when the hinged section 45 is permitted to drop downwardly into the crate, the same will form a partition which 50 when forced upon the tapered block 50 will be held against displacement dividing the said crate into two compartments. The movement of this hinged section 45 will be limited in one direction by the engagement 55 of one of the rails 47 with the slats 20, while movement in the opposite direction will be prevented by the end of the said block 50 which will contact with the opposite end rail 47. In order to permit the engagement 60 of the section 45 behind the block 50 and the sides 16 behind the ends of the bars 36, the top and bottom must be of a sufficient resilient nature to permit their being slightly bent upwardly intermediate their ends.

65 The crate is folded as follows: The top 19

is forced upwardly intermediate its length until the sides 16 are free to move inwardly to rest upon the bottom 18, the top is then pushed longitudinally with respect to the bottom in one direction which permits one 70 of the end sections to lie in the same horizontal plane as the said top 19, and the opposite end section to lie in the same horizontal plane as the bottom 18. Owing to the 75 previously described construction of the L-shaped plates 24, when the crate is collapsed the top and the bottom will be held in spaced relation to each other which permits said 80 crate being folded upon the opposite side sections. When the crate is in its folded position the same will be securely held against displacement by a link 51 secured as indicated by the numeral 52 to the bottom 18, which link engages a pin 53 secured to one side of the bar 36.

The previously described form of crate is used preferably for the purpose of shipping fowl, but it is to be understood that the same is not limited to this use alone, but 90 may contain any objects to which the construction of the various parts will adapt it.

Having thus particularly described this invention, what I claim as new and desire to obtain by Letters Patent, is:—

1. In a crate comprising a plurality of 95 folding sections, a top section having intermediate slats independently hinged with respect to the remainder of the top, transverse bars beneath said top section and supporting the free ends of said independently hinged slats, a block secured to said independently hinged slats for spacing them, a block secured on one of said transverse bars and disposed between said independent slats when in their closed position and a turn-button on said last named block and movable to engage the top sides of said slats for holding them in their closed position.

2. The combination with a crate formed 100 of a plurality of collapsible sections, including a top section, said top section having intermediate slats independently hinged with respect to the remainder of the top to form a closure member for the top of the 105 crate, of a bar extending transversely of the top section, a swinging partition formed of a series of spaced slats hinged to said bar and adapted when in horizontal position to lie against the slats of the top and movable into vertical position to divide the 110 crate into two compartments, means for locking the partition in horizontal position against the top of the crate, and means for locking the independently hinged slats upon 115 the top section.

3. In a crate comprising a plurality of 120 sections forming a closure, a swinging partition adapted to be locked in a horizontal position against the lower side of said top 125

and movable into a vertical position, and means for locking said partition in a vertical position, said means comprising a block secured upon the bottom section and having an inclined upper face, said partition being engageable behind said block by springing said bottom section outwardly.

In testimony whereof, I affix my signature, in presence of two witnesses.

CLARENCE F. MIESEN.
